UNITED STATES PATENT OFFICE.

CHARNOCK H. MC CALL, OF ATLANTA, GEORGIA.

EXHAUST MECHANISM FOR ENGINES.

1,032,016.

Specification of Letters Patent.

Patented July 9, 1912.

Application filed June 1, 1911. Serial No. 630,651.

To all whom it may concern:

Be it known that I, CHARNOCK H. MC CALL, a citizen of the United States, residing at Atlanta, in the county of Fulton and State of Georgia, have invented certain new and useful Improvements in Exhaust Mechanism for Engines, of which the following is a specification.

My invention relates to draft regulators especially designed for use in connection with locomotive boilers, and has particular reference to the construction of the exhaust nozzle and associated parts.

The object of the invention is to provide a simple, practical and economical construction and arrangement of parts which may be operated from the cab of the engine in such a manner as to effectively control the effect of the exhaust in producing the forced draft.

In order that my invention may be readily understood reference is had to the accompanying drawings, forming part of this specification, and in which,

Figure 1 is a longitudinal sectional view through the front end of a locomotive boiler showing my improved nozzle in position therein; Fig. 2 is a horizontal section through the same; Fig. 3 is a side elevation on an enlarged scale of one form of my improved nozzle; Fig. 4 is a plan view thereof.

Referring to the drawings, 1 indicates a boiler shell and 2 the usual fire tubes which discharge into the smoke box.

3 indicates the stack through which the steam and products of combustion escape.

4 indicates a hollow stand or base of my improved nozzle, which is connected with the exhaust of the engine cylinders by means of the usual or any suitable pipes (not shown). The base 4 preferably tapers slightly upwardly, and to its upper edge is pivoted a plurality of annular tapering rings of progressively decreasing diameter. Two of such rings, 5, 6, are shown in the drawing, and these are superposed one upon the other and are so proportioned that they form collectively a frusto-conical cap, the sides of which are of uniform slant.

It will be observed that the lower ring 5, 50 rests snugly upon the upper edge of the base 4 and is hinged thereto at one side, as by means of the hinge 7, while the upper section or ring 6 fits snugly upon the top of ring 5 and is hinged at one side to the base 4, 55 as by means of hinge 8, one member 8' of which extends across section 5 and is secured

at its end to section 6. The hinges 7 and 8 are preferably arranged at opposite sides of the nozzle.

In order to move the rings on their pivots, they may have secured thereto crank arms, from which may extend operating rods 10, 11, to the cab of the engine. With the parts in the position shown in the drawing, the steam is forced to escape through the small opening 9 in the top of the upper ring. By pulling upon rod 10, however, this ring may be swung about its hinge 8 to a position at one side of the nozzle, and then the exhaust is throttled by the larger ring 5. 70 In the same manner this ring 5 may be swung about its hinge 7 to a position at the opposite side of the nozzle, thus leaving the entire opening through the base 4 free and unobstructed. In order to control still further the effect of the exhaust passing through a stack I provide immediately above the nozzle an adjustable discharge pipe arranged directly below the smoke stack. This pipe comprises a fixed section 14 and a movable section 12 adapted to telescope therewith and carrying at its lower edge a flaring petticoat 13. In order that the petticoat pipe may be raised and lowered from the cab of the engine I provide a shaft 15 journaled 85 in brackets secured to the section 14 and extending through a boiler shell. This shaft carries at its outer end a crank to which is pivotally secured a pull rod 18 extending to the cab. Mounted on the shaft 15 at each 90 side of the discharge pipe is a wheel or pulley 16 over which is wound a chain 17 secured to the petticoat 13. It is obvious that by manipulating the rod 18 the pulleys 16 may be rotated and the petticoat pipe raised 95 or lowered relative to the nozzle and in this manner the exhaust steam may be more or less confined in its passage to the stack and the forced draft produced thereby accordingly controlled.

It will thus be seen that in all of its forms my improved nozzle comprises but few parts and is simple and reliable in operation, and it is thought that the many advantages of my invention will be readily appreciated by those familiar with such matters.

What I claim is:

A variable exhaust nozzle for engines comprising a hollow base or stand connected with the exhaust of the cylinders, and a pair of superposed annular rings hingedly sup-

ported upon said base, the hinges being disposed on opposite sides of said base, each of said rings being of frusto-conical shape, the large end of the lower ring being of the same size as and resting upon the top of said base, and the large lower end of the upper ring being the same size as and resting upon the small upper end of the other, and means

for independently moving said rings relatively to each other and to the base.

In testimony whereof I affix my signature in presence of two witnesses.

CHARNOCK H. McCALL.
